RAILWAY TRUCK

Thomas A. Hurtner, Albany, N.Y., assignor to Adirondack Steel Casting Co., Watervliet, N.Y.

Filed Feb. 12, 1962, Ser. No. 172,412

4 Claims. (Cl. 105—182)

This invention relates to an improved truck adapted to be associated with railway cars. The truck of this invention is particularly characterized by its light weight, durability, economy of manufacture and smooth and silent operation.

A great deal of interest presently exists with regard to the provision of economical and efficient structures for railway cars. As metropolitan areas expand, rapid transit systems are being developed, expanded and modernized and it is, of course, desirable to accomplish this with the greatest possible efficiency.

Apart from the expense, severe problems exist in railway transportation relating to the smoothness of the ride and to the noise produced. The design of the trucks for the cars plays a large role in determining smoothness and quietness. With many truck designs, it is necessary, in order to avoid irritating noise, to resort to elaborate insulation or other modifications in the car design.

An additional objection to most truck designs resides in the massiveness of the components thereof and the necessity for various elements which add to the weight of the trucks. Obviously any weight saving in railroad cars is desirable, since a corresponding decrease in the energy necessary to start, stop and transport the cars will result. These energy considerations are particularly critical in rapid transit systems, since a great many stops are made for a given distance of operation.

It is thus apparent that railway trucks which are economical from the standpoint of production costs and maintenance are of considerable importance to the industry. Trucks which combine with these characteristics smooth, quiet and efficient operation and which are also light in weight are particularly desirable.

It is, accordingly, an object of this invention to provide railway trucks which can be economically manufactured and maintained and which are characterized by light weight as well as smooth, quiet operation.

Other objects and advantages of this invention will appear hereinafter, and for purposes of illustration, but not of limitation, specific embodiments of this invention are shown in the accompanying drawings in which—

FIGURE 1 is a side elevation, partly cut away, of a railway truck characterized by the features of this invention;

FIGURE 2 is a plan view of the railway truck shown in FIGURE 1;

FIGURE 3 is a near elevation, partly cut away, of the railway truck shown in FIGURE 1;

FIGURE 4 is a detail view taken about the line 4—4 of FIGURE 2; and

FIGURE 5 is a detail view taken about the line 5—5 of FIGURE 1.

The railway truck of this invention comprises a frame portion having journal boxes located at the corners of the frame portion for supporting the axles and wheels for the truck. The journal boxes employed comprise an arm portion having means for pivotally connecting the boxes to the truck frame. Upstanding portions are also integrally formed in the boxes and resilient members are interposed between these upstanding portions and the truck frame. These resilient members are thus able to react to forces resulting from relative movement between the truck frame and the journal boxes.

2

The truck design of this invention also preferably includes a swivel connection located centrally of the frame for engagement with a railway car whereby the truck swivels with respect to the car in a well known fashion.

5 Spaced laterally of this swivel connection, there are provided support means for locating spring members. The springs are adapted to engage the under side of the railway car and are designed to carry substantially all the weight of the car. Bearing means which are located between the car and the spring means are adapted to be linked to the truck frame in a manner such that improved stability of the car is provided.

Brake means are adapted to be located on the truck frame at the sides of the frame between the wheels 15 on each side and below the spring supporting means. Pistons extend from either end of the brake means and the brake shoes connected to the pistons engage the wheels in a manner such that operation of the brake means results in opposing forces being transmitted to the respective 20 wheels on a given side of the frame.

The accompanying drawings will provide a more detailed illustration of the subject matter of this invention. The railway truck, generally designated by the numeral 10, is shown in FIGURE 1 as it would appear relative to a 25 car body, designated by the line 12, and a railway, designated by the line 14.

The truck includes a frame 16 having interconnecting transoms 18. Pivotedly secured to the frame 16 at the point 20 are the arms 22 which are integrally formed in 30 journal boxes 24. The journal boxes are provided for supporting axles 26 carrying wheels 28.

A vertically extending lug 30 is formed in each journal box 24, and these lugs terminate in faces 32. Resilient 35 inserts 34, which may be bonded rubber sandwiches, are interposed between the faces 32 and faces 36 formed in the frame 16. By reason of the pivotal connection between the boxes 24 and the frame 16, and due to the resilient character of the inserts 34, the journal boxes and frame can be moved relative to each other and the inserts 40 will take up the stresses resulting from this movement.

A pair of supporting seats 38 extends laterally from the frame 16 and is provided for supporting bellows-type air springs 40. The air springs are each connected to an upper member 42 having a bearing surface 44 thereon. 45 These bearing surfaces 44 are adapted to contact the underside of the car body and serve to support substantially all the weight of the car body.

The members 42 are provided with arms 45 which extend downwardly toward the frame 16. Links 46 are pivotally connected to the arms 45 at one end and are connected at their other ends to upwardly extending link brackets 47 and 48. The bracket 47 is formed in the support portion 38 of the frame 16, while the brackets 48 extend upwardly from an inner portion of the frame 16. Lifting lugs 50 secured to the car body are adapted to fit over projections 52 formed in the link brackets 48 to permit interengagement of the truck and car body.

Secured to the sides of the frame beneath the supporting seats 38 is a pair of air brake units 54. These units 60 include pistons 56 which terminate in brake shoes 58. Links 59 are pivotally secured at one end to the frame 16 and at the other end to the brake shoes 58, and these links provide vertical support for the pistons and brake 65 shoes. A snubber 60 is located between members 42 and supporting seats 38.

The car body is adapted to be provided with a swivel connection with the truck at the point 62. The described 70 apparatus may also be provided with a drive means such as may be employed in self-powered rapid transit units. The drive means illustrated includes a drive shaft 64 con-

ected to a power unit (not shown). The drive shaft is connected to universal joints 66 which are associated with a Dana gear drive 68. A shaft 72 extends through opening 74 in the transoms 18 for transmitting the driving force to a similar gear drive unit 70. The specific arrangement of the shaft 72 and transoms 18 is shown in detail in FIGURE 4.

The driving mechanism illustrated is also provided with conventional torque arms 76 which are connected at one end to the gear boxes and at the other end to brackets 78 formed in the frame 16. In considering the truck design, it will be apparent that the specific drive means employed is not critical. It will also be apparent that a drive means can be excluded, as is the case in many truck applications.

FIGURE 5 illustrates in detail the pivotal connection between the arm 22 of a journal housing 24 and the frame 16. This connection includes a pin 80 extending through openings in the arm 22. A resilient bushing 82 is located within an opening in frame 16 and the pin 80 is located within the bushing. Since the unique design of this truck provides for pivotal movement between the journal box 24 and the frame 16, the connection between these members is of critical importance. It is necessary, in addition to insuring against fracture in this joint, to provide for a smooth, silent operation. A Clevite "Silentbloc" bushing is particularly suitable for this arrangement. A resilient bushing of this design permits silent pivotal movement between the members, while at the same time providing allowance for torsional stresses tending to bend the arm 24 transversely of the frame 16.

In the described railway truck design, the vertical loads are carried by the air coil spring combination supported by the one piece frame 16. By locating the springs outwardly of the truck in the manner shown, maximum lateral stability can be achieved, and a substantially constant car body height, independent of passenger load, will result. It will be appreciated that other spring designs, such as steel coils or conical springs, can be employed in place of the air springs. It is desired, however, to locate the springs in the position shown and, in this connection, the provision of the links 46 has also been found to enhance the stability of the system. The location of these links establishes the desired vertical position of the spring axes.

The journal housings 24 are preferably provided with self-aligning spherical roller bearings. The provision of these bearings in the one piece journal housings aids in providing a smooth operation for the trucks.

The direct springing action afforded by the provision of the resilient inserts 34 provides greater rigidity in the railway cars. Bonded rubber sandwiches are particularly suitable for use as the inserts, since they will stand up under shear and compression forces. The four pivoted journal housing assemblies allow for the desired lateral and vertical misalignment of the axle assemblies which is required for equalization of the system. This arrangement eliminates the usual pedestal legs required for guidance of journal boxes, and for transmitting acceleration, deceleration and lateral forces occurring between the axle assembly and the truck frame. The usual wear and noise encountered between the pedestals and journal box wear plates are accordingly eliminated and lateral cushioning of the axle assemblies also reduces wear in the wheel flanges. Furthermore, the journal and equalizer springs are eliminated with this design and a bolster is not required, since the center pin does not carry vertical loads.

Various drive arrangements can be employed with the described trucks including the use of one gear drive per axle, with car body mounted traction motors or torque converters. Parallel mounted traction motors with gear drives mounted to the truck frame, or right angle mounted traction motors with gear drives mounted to the truck frame are also contemplated. As previously indicated, however, the inventive aspects described are not dependent

upon a particular drive and are equally valuable without the provision of any drive means.

The particular brake design illustrated provides distinct advantages in the railway truck. Since the brake shoes are each directed to the inside of the wheels, operation of the brake results in the production of equal but opposite forces. These forces offset each other and minimize transmission of stress to the truck frame.

It will be apparent that there has been described a railway truck characterized by relatively simple construction whereby equipment cost can be substantially reduced. The use of a single cast piece for the truck frame, as well as the use of integral castings for each of the housings 24, is of particular importance from a cost and maintenance standpoint. Furthermore, the design described enables elimination of various equipment conventionally employed and, therefore, the weight as well as the cost of the equipment is reduced. The design also is characterized by smooth operation and a resulting decrease in the transmission of vibrations. Steel-to-steel contact between moving parts is also substantially eliminated and, therefore, a major source of noise is absent in the design of this invention.

The various advantages of the truck of this invention are particularly important in the rapid transit field, since cost, weight, maintenance, etc., are critical factors in this area. However, the concepts of this invention are applicable with regard to all railway trucks and, accordingly, various other applications are contemplated.

It will be understood that various modifications may be made in the above described railway truck which provide the characteristics of this invention without departing from the spirit thereof, particularly as defined in the following claims.

I claim:

1. A railway truck comprising a frame portion, means located centrally of said frame portion for providing a swivel connection with a railway car, support means integrally formed in said frame portion spaced laterally of said connection, spring means located on said support means and provided for engagement with the under side of said car, bearing members located intermediate said spring means and said car, extensions rigidly connected to said bearing members, link means pivotally secured at one end to said bearing member extensions and pivotally secured at the other end to said frame portion, journal boxes located at the corners of said frame portion for supporting the wheels and axles of said truck, arms extending inwardly of said boxes, means for pivotally connecting said arms to said frame, upstanding portions formed integrally with said boxes, and resilient members interposed between said upstanding portions and said frame adapted to react to forces resulting from relative movement between said frame and said boxes.

2. A railway truck according to claim 1 wherein each of said bearing members is provided with two of said extensions including a first extension extending inwardly of said frame and a second extension extending laterally of said frame, and including link means interconnecting each of said extensions and said frame.

3. A railway truck according to claim 1 including brake means located beneath said support means and rigidly attached on the sides of said frame between the wheels on said sides, pistons extending from either end of said brake means and brake shoes connected to said pistons for engagement with said wheels whereby operation of said brake means results in opposing forces being transmitted to respective wheels on said sides.

4. A railway truck according to claim 1 wherein said support means are located whereby the innermost peripheral portions of said spring means are located outside a vertical plane passing through the outer peripheral portions of the rims of said wheels.
